UNITED STATES PATENT OFFICE.

ALBERT HESS, OF FRIEDBERG, GERMANY.

FOLDING CARDBOARD BOX AND THE LIKE.

1,411,724.

Specification of Letters Patent. Patented Apr. 4, 1922.

Application filed May 18, 1912. Serial No. 698,244.

(GRANTED UNDER THE PROVISIONS OF THE ACT OF MARCH 3, 1921, 41 STAT. L., 1313.)

To all whom it may concern:

Be it known that I, ALBERT HESS, a subject of the Emperor of Germany, residing at No. 3 Bismarckstrasse, Friedberg, in the 5 Province of Hessen, Germany, have invented certain new and useful Improvements in Folding Cardboard Boxes and the like, (for which I have filed applications in Germany, May 23, July 3, and October 14, 1911; in 10 France, July 19, 1911; in Belgium, November 6, 1911; in Switzerland, October 19, 1911, and in Austria, May 1, 1912,) of which the following is a specification.

This invention has for its object to provide an improved folding box made preferably of cardboard for use in transporting articles of the most varied kinds.

A box constructed according to this invention is formed of two blanks, one of which 20 consists of a central portion or top panel provided with a hand grip and having a panel hinged to each of two opposite ends, and means on these panels for securing the blank to the central portion of a second blank. This second blank comprises a central portion having at two opposite ends hinged covering panels adapted to cover the space formed by arranging the side panels at right angles to its central portion. To 30 each of these hinged covering panels is hinged a closing panel which when the box is set up, overlaps the top panel or central portion of the first mentioned blank; being provided with a slot through which the hand-grip passes. The hand-grip in this 35 way aids in holding the sides of the box, when closed in their relative positions.

Ordinarily, the panels are hinged one to another by means of folding creases as is 40 customary with cardboard boxes.

The figure is a perspective view of my invention in which the flaps are provided on the covering panels, the box being shown partly erected.

45 Referring to the drawing which shows the parts of the cardboard or the like blanks from which the boxes is made, 1 is the rectangular bottom panel to which are connected the two side panels 2 and 3, of which the former has joined to it a panel 4 and the latter a panel 5. The panels 4 and 5 are formed each with a slot 10, 11. The blanks for the frame 1 consist of a top panel 6 and panels 7 and 8 connected thereto. The 55 panels 7 and 8 are provided at their ends

with strips 7^a and 8^a, and at their sides side strips 2^b and 3^b. The panels are connected to one another, and to their strips by creases indicated in the drawings by lines and formed by scoring. The covering panel 6 is 60 provided with a hand-grip 9 composed of the same material as the panel.

The folding box is formed by bending the panels 7 and 8 at right angles to the panels 6 then the strips 7^a and 8^a are in their turn 65 bent at right angles, and the frame thus formed is placed upon the bottom panel 1 so that the outer edges of the strips 7^a and 8^a are flushed with the ends of this panel. Then the strips are united to the bottom 70 panel, for instance by pasting, fastening or the like. The result is an erect frame having two openings at opposite sides.

The panels 2 and 3 are then bent against the frame so as to close its open sides. Then 75 the panel 5 is placed over the covering panel 6 in such a manner that its slots 11 (corresponding in dimensions to the handgrip 9 but so as to allow of a slight amount of play) is drawn over the grip. In the same 80 manner the panel 4 with its slot 10 is drawn over the grip 9 and the panel 5. By passing the grip 9 through both slots 10, 11 the folding box is secured against coming open accidentally. Since however the folding box 85 thus formed is still open between the vertical edges of the frame 1 and the panels 2 and 3, so that it is possible for the hand to be inserted from outside into the box or for articles contained therein to fall out, the flaps 90 2^b and 3^b are provided which are turned in against the frame 1, after it has been erected, so as to cover the openings above referred to. Before the panels 2 and 3 are bent 95 against the erected frame 1, the flaps which are situated in the same plane as the panels 2 and 3, are first bent at a slightly greater angle than a right angle so as to project into the space inclosed by the frame 1 the flaps 3^b extending the full width of the box, and 100 overlapping the adjacent flaps 2^b of the panel 2 so as to afford a clamping action.

What I claim is:

A collapsible box comprising a central frame portion provided with open sides, said 105 frame portion being enclosed by side panels and overlapping top panels, each of said side panels having vertical retaining flaps disposed within said frame the retaining flaps of one side panel extending the full width 110

of the box and overlapping the adjacent flaps of the other side panel so as to afford a clamping action, the top panels being provided with registering slots, and a handle member secured to the top of the frame member and extending through the slots of the overlapping top panels.

In testimony whereof I have signed my name to this specification in the presence of two subscribing witnesses.

ALBERT HESS.
